(57) **CLAIM**

The ornamental design for a multiple hook supported planter, as shown and described.

DESCRIPTION

FIG. 1 is a top front right side perspective view of a multiple hook supported planter showing my new design;

FIG. 2 is a top plan view thereof;

FIG. 3 is a front side elevational view thereof;

FIG. 4 is a left side elevational view thereof; the right side elevational view being a mirror image thereof;

FIG. 5 is a rear side elevational view thereof; and,

FIG. 6 is a bottom plan view thereof.

The broken-lines in the drawings show portions of the multiple hook supported planter that do not form part of the claimed design.
